UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed December 11, 1918. Serial No. 266,813.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

This invention relates to mining machines, and especially, although not exclusively, to coal cutting machines of the longwall type, wherein a flat sided jib or cutter bar, provided with a cutter chain, projects in a substantially horizontal plane from one end of a casing to which it is pivoted and wherein an electric or other motor contained in the said casing propels the machine by means of a flexible feeding member, usually a cable or chain, which is anchored at one end and 20 which passes around guide sprockets or pulleys carried on what is hereinafter described as the "leading" end of the casing or the end thereof opposite the cutter bar, and also around a feed sprocket or drum 25 driven by said motor.

When in use in longwall undercutting, the cutter bar can be swung to one side or the other of the casing at right angles to the length thereof and projects under the coal, 30 and the feed member or chain lies as close as possible to the longwall face which is being undercut and passes over one of the guide sprockets or pulleys, which is also located as close as possible to the face, in 35 order that the pull of the feed chain shall tend to keep the casing close alongside the face and shall not exert any turning moment tending to slew it horizontally.

Heretofore the machine could be propelled only in one direction, i. e. forward, or in the direction of the end thereof opposite the cutter bar, along the mine face, by means of the feed mechanism above referred to, and a primary object of this invention is to provide means whereby the machine can also be propelled in the opposite direction, i. e. in the direction of the cutter bar end thereof, as is frequently desirable.

Another object of the invention is to provide an attachment which is readily applicable to existing mining machines, said attachment comprising auxiliary guiding means for the flexible feeding member, whereby the movements of the machine are controlled, and particularly whereby the di-

rection of travel of machines of the longwall type may be reversed, as above mentioned.

The foregoing and other objects of the invention, together with means whereby the same may be carried into effect, will best be understood from the following description of certain forms or embodiments thereof shown for purposes of illustration in the accompanying drawings.

In said drawings:

Fig. 1 is a top plan view of a coal cutting machine of the longwall type, illustrating the usual operation and direction of travel of such a machine.

Fig. 2 is a similar view of the same machine, showing said machine as provided with means, embodying the present invention, whereby the same may be fed in the opposite direction, the cutter bar being shown as projecting at right angles from the right hand side of the casing of the machine, looking in the direction of travel thereof.

Fig. 3 is a view substantially similar to Fig. 2, but showing the cutter bar projecting at right angles on the other side of the casing.

Figs. 4 and 5 are a top plan view and an end elevation, respectively, showing the guiding member detached.

Fig. 6 is a part top plan view showing a modified construction.

Referring first to Fig. 1, there is shown therein a coal cutting machine of the well known longwall type comprising a main frame or casing A, to one end of which a flat sided jib or cutter bar B is pivoted at B¹ to swing about an axis transverse to the cutting plane, and about which travels a cutter chain C provided with reversible cutter bits C¹. Mounted in the central portion of the casing A is an electric or other motor D which, through suitable transmission mechanism E, E¹, actuates a sprocket wheel F for driving the cutter chain. At the other end of the casing A is mounted the feed mechanism, designated as a whole by the letter G, comprising a feed drum or sprocket G¹ which is connected by suitable transmission mechanism H with the shaft D¹ of the motor and cooperates with the flexible feed member or chain J, and guide pulleys or sprockets G², G³ and G⁴, which also cooperate with the feed chain J, and two of which, namely the sprockets G² and G⁴, are situated

on opposite sides of the casing with their peripheries extending beyond the sides thereof, while the third, namely the sprocket G^3 , is located between the sprockets G^2 and G^4 in the center line of the casing. The feed chain J is securely anchored at one end, as by a suitable jack K situated close to the face L that is being cut, and extends as close as possible along said face to the guide sprocket G^2 , around which it passes to the guide sprocket G^3 , thence around the feed sprocket G^1 and around the third guide sprocket G^4 , where the other end is paid off. Owing to this arrangement of the feed mechanism and the anchored feed chain, when the machine is at work the casing is kept close to the face, with which it is parallel, and this result is aided by the reaction of the cutter chain C in the act of cutting, which acts on the "following" or cutter bar end of the casing to keep the casing close up to the wall. Such an arrangement of the feed mechanism permits of the machine being fed in only one direction, as indicated by the arrow M . It is sometimes desirable, however, to be able to back the machine, that is to say, to cause the same to be so fed that, while cutting coal, the travel of the casing will be in the opposite direction along the same face. In this event the cutter bar end of the casing, which is usually the "following" end, will become the "leading" end, and the feed mechanism end, which is usually the "leading" end, will become the "following" end and will trail along after the cutter bar. When the machine is thus cutting backwards the direction of movement of the cutter chain C must be reversed after the cutter bits C^1 shall have been correspondingly reversed in their position upon the chain. According to the present invention this backing or reverse feeding of the machine can be effectively performed with a minimum addition of parts to machines otherwise constructed as usual, by the provision on the cutter bar end of the machine of additional guide sprockets N^1 and N^2 , as shown in Fig. 2. These sprockets are supported in, or approximately in, the plane of cut of the machine; the sprocket N^2 being so mounted as to be located as close as possible to the face L , and in advance of the cutter bar B , that is to say, forward of it in the new direction of travel of the casing as indicated by the arrows Q ; while the sprocket N^1 is mounted substantially in line with the other side of the casing. It will be seen that the two sprockets N^1 and N^2 , at the one end of the casing, are respectively in line with the two sprockets G^2 and G^4 , at the other end, and are at opposite sides of the casing. The feed chain J , which is now anchored to a jack K set ahead in the direction of the arrows O close up to the face, extends as close as possible along the face, passes around the addi-

tional guide sprocket N^2 and then around the second additional guide sprocket N^1 , whereupon the chain passes along the side of the casing and around the guide sprocket G^4 , then around the feed sprocket G^1 , and afterwards around the remaining guide sprockets G^3 and G^2 , where the slack chain is paid off. When the motor D is driven in the reverse direction as compared with its direction of rotation in the machine as shown in Fig. 1, the machine will be propelled backwards in the direction indicated by the arrows O , and the pull of the feed chain will again tend to keep the casing close alongside the face, this being aided as before by the reaction of the cutter chain, which now travels in a direction opposite to that indicated in Fig. 1.

Fig. 3 shows the same machine as shown in Fig. 2 with the cutter bar B swung around on its pivot to the other side of the casing, and with the additional guide sprockets N^1 , N^2 mounted in a corresponding position relative to the cutter bar. The sprocket N^2 is now situated on the opposite side of the casing as compared with its position in Fig. 2, but it is again situated as close as it is possible to the face L^1 in advance of the cutter bar in the direction of travel indicated by the arrows O . The feed chain J is again led from the anchor K , also situated close to the face, and passes around the guide sprockets N^2 , N^1 , along the side of the casing, and then around the guide sprocket G^2 , the feed sprocket G^1 , and the guide sprockets G^3 and G^4 , where the slack end is paid off. It will therefore be seen that this machine is arranged to cut a face L^1 situated on the side of the casing opposite to that cut by the machine shown in Fig. 2, the machine being fed backwardly by the motor in both cases.

As shown in Figs. 4 and 5, the above mentioned additional guide sprockets N^1 and N^2 are conveniently pivotally mounted on a bracket or arm P which is provided with apertured ears or lugs P^1 , P^2 through which can pass vertical pins or bolts Q^1 , Q^2 , respectively, for detachably securing the bracket in place, these bolts being disposed parallel with the axis of swing of the jib, and preferably received in the unused pair of the three apertures P^3 usually provided radially about the bar pivot for the purpose of selectively receiving the pin or bolt Q^3 , which in turn extends into a registering aperture (not shown) in the bar and thereby holds the latter in its longitudinal or different lateral positions relative to the casing. It will be seen that the arm or bracket P is reversible and, as shown in Figs. 2 and 3, can be mounted on the end of the casing A with the sprocket N^2 situated at the one side or the other thereof, as required by the position of the machine relative to the face which is being cut, the bolt Q^3

Q^2 being correspondingly on the one side or the other of the casing. The bracket or arm P is preferably slotted at P^4 to form passages for the coal cuttings.

5 Fig. 6 shows a modified arrangement of the additional guide sprockets N^1 , N^2 on the cutter bar end of the casing. In this modified construction the sprockets N^1 and N^2 are each mounted on a bracket R^1 , R^2 , 10 respectively, bolted to the casing A , by which brackets they are overhung into the plane of cut. The operation of the sprockets in conjunction with the feed chain J is, however, the same as described above with 15 reference to Figures 2 and 3.

For convenience and brevity of description, the flexible feeding member J is herein frequently referred to as a feed chain, and the members G^1 , G^2 , N^1 , N^2 , etc. as sprockets, 20 although the member J may equally well be a rope or cable, and the other members pulleys, drums, or the like, in accordance with several types of feed mechanism of this general character well known in the art, and 25 the terms herein employed are to be understood as including all such well known equivalents.

While I have in this application specifically described several forms which my invention may assume in practice, it will be understood that these forms of the same are shown for purposes of illustration and that the invention may be modified and embodied in other forms without departing 35 from its spirit or the scope of the appended claims.

What I claim as new and desire to secure by Letters Patent is:

1. In a mining machine, a casing, a laterally extending cutter bar at one end thereof, feeding mechanism on the opposite end of said casing, guiding means disposed on said casing adjacent said bar and the face, and a flexible feed member cooperating with 45 said feeding mechanism and having a transversely extending portion engaging said guiding means.

2. In a mining machine, a casing, a laterally extending cutter bar at one end thereof, feeding mechanism on the opposite end of said casing, a plurality of guiding members disposed on said casing adjacent and substantially parallel to said bar, and a flexible feed member cooperating with said feeding 55 mechanism and consecutively engaging said guiding members.

3. In a mining machine, a casing, a laterally extending cutter bar at one end thereof, feeding mechanism on said casing, a bracket on said casing having a cutting passage, a plurality of guiding members on said bracket adjacent and substantially parallel to said bar, and a flexible feed member 60 cooperating with said feeding mechanism and 65 engaging said guiding members.

4. In a mining machine, a longwall machine casing slidable on a mine bottom, a cutter bar carried on an end thereof and disposed laterally relative thereto, at either side thereof, and flexible feeding and 70 guiding means for advancing the bar carrying end of said casing along a face when said bar is in either lateral position.

5. In a mining machine, a longwall machine casing slidable on a mine bottom, a 75 cutter bar carried on one end thereof and disposed laterally relative thereto at either side thereof, and flexible feeding and guiding means including a guiding member adjacent the face for advancing the bar carrying end of said casing along the face in either position of said bar.

6. In combination, a mining machine having a bar disposable laterally at either side thereof, a guide carrying bracket disposable 85 transversely relative to one end of said machine, guides thereon, and means for supporting said bracket in reverse transverse positions in different positions of said bar.

7. In combination, a mining machine having a bar disposable laterally at either side thereof, a guide carrying bracket disposable 95 transversely relative to one end of said machine and having provision for the passage of cuttings therethrough, and means for supporting said bracket in reverse transverse positions in different positions of said bar.

8. In a mining machine, a longwall machine casing slidable on a mine bottom, a cutter bar pivoted at one end thereof and 100 disposable relative thereto laterally at either side thereof, feeding mechanism on the other end of said casing, a flexible feeding member 105 cooperating with said mechanism, and guiding means for said member supported adjacent the bar pivot in either lateral position of said bar.

9. In a mining machine, a longwall machine casing slidable on a mine bottom, a cutter bar pivoted at one end thereof and 110 disposable relative thereto laterally at either side thereof, feeding mechanism on the other end of said casing, a flexible feeding member 115 cooperating with said mechanism, and guiding means for said member adjacent the bar pivot and the face in either lateral position of said bar.

10. In a mining machine, a longwall machine casing slidable on a mine bottom, a cutter bar pivoted at one end thereof and 120 disposed relative thereto laterally at either side thereof, feeding mechanism on the other end of said casing, a flexible feeding member 125 cooperating with said mechanism, and guiding means for said member supported adjacent the bar pivot and on opposite sides of one end of said casing in either lateral position of said bar.

11. In a mining machine, a longwall machine casing slidable on a mine bottom, a 130

- 4 cutter bar pivoted at one end thereof and disposable relative thereto laterally at either side thereof, feeding mechanism on the other end of said casing, a flexible feeding member 5 cooperating with said mechanism, and a plurality of cooperating guiding means located adjacent the bar pivot and in either lateral position of the bar disposable one on said casing and the other adjacent the face.
- 10 12. In a mining machine, a casing movable lengthwise along a face, a laterally extending cutter bar at one end thereof, feeding mechanism at the other end thereof, a flexible feed member, and guiding means therefor at the bar supporting end of said casing comprising a guide support and rotatable guiding elements thereon having their axes located substantially in a line parallel to the longitudinal axis of said bar and located on opposite sides of one end of said casing.
- 15 13. In a mining machine, a casing movable lengthwise along a face, a cutter bar disposable laterally at either side thereof, feeding mechanism at the other end thereof, a flexible feed member, a bracket fixed to the bar supporting end of said casing, guiding members carried on said bracket and disposed one adjacent one side of one end of said casing and the other adjacent the face, and means supporting said bracket in reverse positions of said bar.
- 20 14. In a mining machine, a casing, a pivoted laterally extendible cutter bar on one end thereof, means for holding said bar in different angular positions on said casing including a pin and a plurality of apertures radially located relative to the bar pivot, a guide carrying member disposed adjacent the pivot of said cutter bar, guiding means thereon, and means for securing said member in position, said means being located in an unused aperture.
- 25 15. In a mining machine, a casing, a pivoted laterally extendible cutter bar on one end thereof, means for holding said bar in different angular positions on said casing including a pin and a plurality of apertures radially located relative to the bar pivot, a guide carrying member disposed adjacent the pivot of said cutter bar, guiding means thereon, and means for securing said member in position, said means being located in a plurality of unused apertures.
- 30 16. A mining machine attachment comprising a substantially L-shaped bracket having a plurality of guiding members, one located at the extremity of one of its arms and the other located adjacent the junction of its arms, and means for attaching said bracket to a mining machine.
- 35 17. A mining machine attachment comprising a substantially L-shaped bracket hav-
- ing a plurality of guiding members thereon, one located at the extremity of one of its arms 65 and the other located adjacent the junction of its arms, said bracket also having provision for permitting the passage of cuttings therethrough.
- 40 18. A mining machine attachment comprising a substantially L-shaped bracket having a plurality of rotatable sprockets, one located at the extremity of one of its arms and the other located adjacent the junction of its arms, and means for attaching said bracket to a mining machine including an aperture in its other extremity and a cooperating aperture.
- 45 19. A mining machine comprising, in combination, a casing, a cutter bar pivoted to said casing at one end thereof and adapted to occupy a position transverse thereto at either side thereof, and means for feeding said machine across the mine face comprising a flexible feeding member and a member provided with a plurality of devices for guiding said flexible member at the end of said casing adjacent said cutter bar, said last named member being reversible to position either of said guiding devices at either 80 side of said casing.
- 50 20. In a mining machine, the combination with a casing, of a cutter bar pivoted to one end of said casing to swing to either side thereof about an axis transverse to the cutting plane, a set of sprockets including a feed sprocket, all mounted on the end of the casing opposite to that at which the cutter bar pivot is situated, a second set of sprockets carried by that end of the casing at 100 which the cutter bar pivot is situated, two of the sprockets of each set being situated respectively adjacent opposite sides of the casing, a motor in the casing operatively connected with said feed sprocket, and a feed 105 chain cooperating with sprockets in both of said sets to feed the machine.
- 55 21. In a mining machine, the combination with a casing, a cutter bar pivoted to one end of said casing to swing to either side thereof about an axis transverse to the cutting plane, and a set of sprockets including a feed sprocket all mounted on the end of the casing opposite to that at which the cutter bar pivot is situated, of a second set of sprockets, 110 an arm carrying said second set, bolts for securing said arm to that end of the casing at which the cutter bar pivot is situated, two of the sprockets of each set being situated respectively adjacent opposite sides of the casing, a motor in the casing operatively connected with said feed sprocket, and a feed 115 chain cooperating with sprockets in both of said sets to feed the machine.
- 60 22. In testimony whereof I affix my signature.
- MORRIS P. HOLMES.

Certificate of Correction.

It is hereby certified that in Letters Patent No. 1,428,505, granted September 5, 1922, upon the application of Morris P. Holmes, of Claremont, New Hampshire, for an improvement in "Mining Machines," errors appear in the printed specification requiring correction as follows: Page 3, line 60, claim 3, for the word "cutting" read *cuttings*; same page, line 121, claim 10, for the word "disposed" read *disposable*; and that the said Letters Patent should be read with these corrections therein that the same may conform to the record of the case in the Patent Office.

Signed and sealed this 31st day of October, A. D., 1922.

[~~SEAL.~~]

KARL FENNING,

Acting Commissioner of Patents.
